Primary Examiner — Kelley Donnelly

(57) **CLAIM**

The ornamental design for a head support, as shown and described.

DESCRIPTION

FIG. 1 is an exploded perspective view of the head support, according to my new design, here shown in an open position; FIG. 2 is an enlarged perspective view of the head support in FIG. 1;

FIG. 3 is a top elevational view of the head support in FIG. 2; FIG. 4 is a distal end elevational view of the head support in FIG. 2;

FIG. 5 is a side elevational view of the head support in FIG. 2, an opposite side elevational view being a mirror image thereof;

FIG. 6 is an exploded perspective view of the head support in FIG. 1, here shown in a closed position;

FIG. 7 is an enlarged perspective view of the head support in FIG. 6;

FIG. 8 is a top elevational view of the head support in FIG. 7; FIG. 9 is a distal end elevational view of the head support in FIG. 7; and,

FIG. 10 is a side elevational view of the head support in FIG. 7, an opposite side elevational view being a mirror image thereof.

The portions shown in broken line being for illustrative purpose only and form no part of the present design. The various shading styles that can be seen in the drawings represent varying materials.

The dash-dot-dash broken lines that define the bounds of the claimed design form no part thereof.
